UNITED STATES PATENT OFFICE.

DANIEL E. REAGAN, OF COLUMBUS, OHIO, ASSIGNEE OF ONE-THIRD TO WILLIAM DRAYTON, OF SHAWNEE, OHIO.

BRICKMAKING-MACHINE.

1,146,594.

Specification of Letters Patent. Patented July 13, 1915.

Application filed January 29, 1915. Serial No. 5,059.

To all whom it may concern:

Be it known that I, DANIEL E. REAGAN, a citizen of the United States, and a resident of Columbus, in the county of Franklin and State of Ohio, have invented certain new and useful Improvements in Brickmaking-Machines; and I do hereby declare the following to be a full, clear, and exact description of the invention, such as will enable others skilled in the art to which it appertains to make and use the same.

My invention relates to an improvement in brick making machines.

Heretofore in the manufacture of paving bricks or blocks having projections on one or more faces for holding them apart so as to permit the cement, grout or other filler commonly used for bonding purposes, to be readily poured or inserted between the bricks or blocks, and which also facilitate the laying of said bricks by keeping them in alignment, these projections have been formed by repressing the bricks, and also by rollers or other pressure devices applied to the clay bar after the latter has been shaped or molded by the die. These devices are objectionable because of the cost of repressing, and where the rollers or other pressure devices are located beyond the die, the subsequent application of pressure to the clay bar deforms the clay bar, and unless the pressure be considerable, the clay will not be forced up from the unconfined clay bar into the recesses in the roller or other pressure device, so as to form the projections, regular in size and shape.

The object of my invention is to provide a roller which forms one side of a face of the die, so that the clay as it is forced through the die will be forced positively into any recesses in the latter.

A further object is to provide means for rotating the roller section of the die at the same speed of travel of the clay bar through the die, so that there will not be any dragging or shearing strains on the said lugs or projections.

With these and other objects in view, my invention consists in the parts and combinations of parts as will be more fully described and pointed out in the claims.

In the accompanying drawings, Figure 1 is a view in perspective of the die end of a brick making machine showing my improvement applied thereto; Fig. 2 is a view in

longitudinal section through one of the dies; Fig. 3 is a view in front elevation of the die plate carrying the roll and driving gear for same; Fig. 4 is a plan view and Fig. 5 a view in end elevation of the same.

In the drawings I have shown a double stream die for making two clay bars at a time, but I would have it understood that my improvement is equally applicable to a single die machine.

1 represents the head of a brick making machine, to which the die is attached and through which the clay is forced, and 2 is a gate secured to the outer open end of the head 1 by the hinges 3^a at one side and by 65 bolts at the other side.

Secured to the gate 2 is the die plate 3 having an opening or openings therein conforming to the opening in the gate and carrying the dies or die 4, which latter are integral with plate 3 and are of the usual size, shape and construction except that the top is open to receive the roll 5, which latter forms the top of the die, while the sides and bottom thereof are formed by the rigid bottom and side walls 6 and 7 respectively, formed integral with each other and also with the die plate. The sides or side walls 7 of the die are connected at their outer ends by the integral cross member 8, and the side 75 members are provided at their top with the semicircular bearings 9 in which the shaft 10 having the rolls 5 thereon, are mounted and in which it is secured by the removable half bearings 11, secured by screws to the upper edge of the side walls of the die. The rolls 5 may be integral with the shaft 10 or made separate therefrom and secured thereto by keys or otherwise. The roll or rolls are so located with respect to the head 90 95 1 of the machine, that the shape of the clay bar or column, is not fixed or complete until it engages the roll, so that the pressure against the clay which forces the latter out through the die, will force it up and into contact with the roll, thus causing the clay to enter and fill the recesses 12 in the rolls and produce corresponding projections on the upper face of the clay bar or column, while the smooth portion of the surface of the roll acts as a wall for the die. The top wall of the die, or the lower face of cross bar 8 is elevated sufficiently so as not to engage the projections on the clay bar or column.

110

The rolls, or roll shaft 10, is provided at one end with the pinion 13, which meshes with the large gear 14, secured on shaft 15 which is mounted at one end in bearing 16 formed in a side wall 7 of the die, and at the other end in bearing 17 formed at the end of bracket 18 which latter is secured by bolts to the die plate 3, which as shown in Fig. 1, extends to one side of the head 1 of the machine. Secured to shaft 15 is the small sprocket pinion 19, which is geared to sprocket gear 20 by the sprocket chain 21. Gear 20 is secured to shaft 22, carrying pulley 23 which carries the clay bar or column conveyor belt 24, onto which the clay bar passes after it leaves the die. This belt may be positively driven to carry the molded clay bar or column away from the dies and to the cutters or it may be driven by the weight of the traveling bar of clay. The gearing between the pulley 23 and the rolls 5 are so proportioned that the rolls are turned at exactly the same speed as the bar of clay travels after it leaves the mouth of the die so that there shall not be any shearing or dragging strains on the projections 25 formed on the clay bar 26, or any pulling or dragging stresses on the bar 26 itself, which would tend to disrupt the homogeneity of the bar or the lugs or projections and the bar.

This improvement is designed to be attached to any stiff mud brick machine and preferably on a double stream die, which makes two bars or columns of clay at a time, but it should be understood that it is equally applicable to a single stream die. With this improvement, the roll is not a pressure roll in the sense that it is forced by spring or otherwise against a surface of a made bar of clay, nor is it to a fixed roll located beyond the die and acting on a surface previously shaped by the upper wall of the die, but on the contrary, it is mounted in fixed bearing 45 and at a point where the clay being forced into the die is under pressure so that the recesses in the roll will be filled by the pressure forcing the clay outwardly and not by the expansion of the clay bar after it has 50 been shaped. In other words the rotating roll forms the top member of the die and shapes the top surface of the clay bar or column. Again while I have shown a roller for operating on one face of the bar, two

may be used for shaping two faces, but I prefer one. The lugs or projections 25 are preferably curved as shown and are so located that each brick or block formed will have a plurality of projections on one side, which as before explained operate to hold the bricks or blocks sufficient distance apart while being laid to permit the cement grout or other filler to be readily poured or inserted between the bricks, and to keep them in alignment.

It is evident that many slight changes might be resorted to in the relative arrangement of parts shown and described without departing from the spirit and scope of my invention. Hence I would have it understood that I do not wish to confine myself to the exact construction and arrangement of parts shown and described but

Having fully described my invention what I claim as new and desire to secure by Letters-Patent, is:—

1. In a brick making machine, the combination of a die having a plurality of rigid walls and a positively driven roll located intermediate the ends of the die and projecting into the die opening beyond the plane of the adjacent wall, the said roll having a recess in its periphery for forming a projection on the surface of the clay bar or column, and so located with relation to the other parts of the die that the pressure at the rear forces the clay into the recess in the roll, the said roll imparting the final shape to one face of the clay bar.

2. In a brick making machine, the combination of a die having a plurality of rigid walls, a roll forming one wall of the die, a conveyor belt mounted on a carrying pulley, and gearing connecting said pulley and the die roll whereby the latter will be rotated at the same speed of travel as the conveyor belt, the said roll having a recess in its periphery and so located with relation to the other parts of the die, that the pressure at the rear forces the clay into the recess in the roll.

In testimony whereof, I have signed this specification in the presence of two subscribing witnesses.

DANIEL E. REAGAN.
